UNITED STATES PATENT OFFICE.

CLYDE J. COLEMAN, OF NEW YORK, N. Y.

HEAT INSULATION.

946,772.

Specification of Letters Patent. Patented Jan. 18, 1910.

Application filed October 12, 1907. Serial No. 397,071.

To all whom it may concern:

Be it known that I, CLYDE J. COLEMAN, a citizen of the United States, residing in the borough of Manhattan, city of New York, in the county of New York and State of New York, have invented a certain new and useful Improvement in Heat Insulation, of which the following is a specification, reference being had therein to the accompanying drawings, forming part thereof.

My invention relates generally to heat insulation and relates particularly to heat insulating walls of substantially large dimensions such as in cold storage buildings, refrigerator cars and household refrigerators and the like.

The objects of my invention are efficiency, economy and simplicity, and my invention also has other objects and advantages which will appear from the following description.

My invention employs an assemblage of vacuum inclosing bodies as a principal part of the heat insulating construction.

The high efficiency of a vacuum as a heat insulator has been long known, but heretofore no practical embodiment of the same has been made in heat insulating walls of any considerable size adapted to the uses above noted.

My invention is directed to the production of vacua-inclosing heat-insulating walls of any desired dimensions.

To these ends my invention includes an assemblage of vacuum inclosing bodies adjacently arranged so as to form a continuous heat barrier.

My invention also includes a particular conformation of the vacuum inclosing bodies and an overlapping arrangement of the same so as to secure the maximum practicable length of path through the wall along adjacent portions of the vacuum inclosing bodies.

My invention also includes, in combination, low heat conductive cushioning gaskets interposed between adjacent vacuum inclosing bodies.

My invention also includes several details of construction and other advantageous features which will hereinafter appear.

I will now describe my invention with reference to the accompanying drawings and will thereafter point out my invention in claims.

Figure 1 is a transverse section of a portion of a heat-insulating wall embodying my

invention. Fig. 2 is a detail view showing in transverse section one of the U-shaped vacuum inclosing tubes or units seen in Fig. 1. Fig. 3 is an elevation of one of the vacuum inclosing bodies or tubes with portions broken away. Fig. 4 is a view similar to Fig. 1 showing a modification of my invention. Fig. 5 is an elevation, with portions broken away, of one of the vacuum inclosing bodies shown in Fig. 4. Fig. 6 is a sectional elevation, with portions broken out, of a household refrigerator embodying the form of my invention shown in Figs. 1, 2 and 3. Fig. 7 is a view similar to Figs. 1 and 4 but showing another modification of my invention. Fig. 8 is a face view of the wall seen in Fig. 7, partly in section and with the front plate removed. Fig. 9 is a transverse section of a portion of a wall embodying yet another modification of my invention. Fig. 10 is a face view or front elevation of the wall construction seen in Fig. 9, with the front plate removed. Fig. 11 is a transverse section on an enlarged scale, of one of the vacuum inclosing units shown in Figs. 9 and 10. Fig. 12 is a reversed or back view of one of the vacuum inclosing units shown in Figs. 9, 10 and 11. Fig. 13 is a view similar to Fig. 11 of a further modified construction of vacuum inclosing units.

In the embodiment of my invention illustrated in Figs. 1, 2, 3 and 6 of the drawings elongated vacuum inclosing bodies or vacuum tubes 1 are provided, such tubes being composed of vitreous low heat conductive material such as glass, and are formed in one piece or integral and are hermetically sealed or closed at the ends as indicated in Fig. 3 at the bottom. The vacuum inclosing tubes 1 are adjacently assembled in a wall structure to produce a continuous heat barrier, the effectiveness of which is increased by the shape or conformation of the vacuum inclosing tubes 1 and by the manner of their arrangement or in which they are assembled to form the heat barrier.

The heat insulating wall shown in Fig. 1 may be considered as identical with or as a portion of one of the walls of the refrigerator construction illustrated in Fig. 6. In this wall construction outer wall portions or outer plates 2 and inner wall portions or inner plates 3 are provided there being an air space between the plates 2 and 3, but a portion of the space between the plates 2 and 3 is occupied by the heat barrier of my

invention which is shown as arranged adjacent to the outer plate 2, the vacuum inclosing tubes 1 being cushioned from the plate 2 by a sheet 4 of low heat conductive material.

5 The vacuum inclosing tubes 1 are provided with pressure resisting shells and are transversely U-shaped or U-shaped in cross section, and the U legs of each tube extend substantially parallel to each other for an appreciable distance as clearly shown in Figs. 1 and 2. In actual practice the vacuum inclosing tubes 1 are of about the size or dimensions in cross section shown in Figs. 1 and 2 of the drawings, and the small size together with the curved shape or U-shape enables the shell of the tube 1 to withstand or successfully resist the outer atmospheric pressure caused by the inclosed vacuum space. The transversely U-shaped vacuum tubes 1 are arranged in two adjacent parallel layers, the tubes of one layer breaking joints with the tubes of the other layer. The tubes of the first layer or outer layer are arranged or assembled side by side adjacent one to another and with the U legs all extending in the same direction and extending toward the inner side of the wall. The vacuum inclosing tubes of the second or inner layer are arranged or assembled in like manner but with the U legs extending in the opposite direction or toward the outer side of the wall. The U legs of each of the layers extend between and interlock with the U legs of the adjacent layer, a U leg of 35 two of the tubes 1 in one layer being received between the U legs of one of the tubes 1 in the other layer in each instance. Therefore all of the U legs in both layers lie parallel with each other in a direction transverse to or along planes perpendicular to the wall, and also the U legs of the two layers lie successively adjacent in such manner that two U legs of one layer alternate with two U legs of the other layer in a plane parallel with the wall. The U-shaped vacuum inclosing tubes thus overlap one with two others in a plane parallel with the wall and also in planes perpendicular to the wall. Although the vacuum inclosing tubes 1 are 50 particularly and specifically described as transversely U-shaped, with perfect propriety and correctness such tubes may be broadly designated as grooved or as provided with grooves, because the open side of 55 the U constitutes a groove, and in the construction of heat barrier shown portions of two adjacent vacuum tubes enter the groove of a third vacuum tube. A sheet 5 of low heat conductive material is placed between the two layers. The sheet 5 extends continuously from groove to groove around inside of the U of each tube of the two layers. Low heat conductive gaskets 6 are interposed between adjacent tubes 1 of each layer 60 and lie between the adjacent outer sides of

the U legs. The sheet 5 and the gasket 6 serve the same purposes and have triple functions, to wit: first, to cushion the tubes 1 from each other and prevent breakage; second, to provide an effective seal between the tubes to prevent the passage of air; and third, to provide additional heat-insulation to prevent the transfer of heat from tube to tube by conduction. It is evident that the packing or gaskets 5 and 6 should be water proof, and also that they should be yieldable at the time the wall is put together at least. The gaskets 5 and 6 may be composed of waterproof paper, and if desired they may be coated with shellac or other adherent so as to cement all of the tubes together into a substantially integral structure. The gaskets 6 are short enough as shown so as not to make contact with the sheet 5, for preventing the conduction of heat directly from the one to the other.

Heat cannot pass by conduction or convection through the vacua of the tubes 1, and for heat to pass through the wall between the tubes by conduction along the walls thereof or along the interposed packing it must follow a very long and tortuous non-continuous path through low heat conductive materials, such low conducting path being of much greater length than the thickness of the heat-insulating wall. Heat transference by radiation across the vacua will be practically negligible, but means are provided to prevent it. To this end the vacuum inclosing tubes 1 are silvered on the inside; or they may be coated with white enamel or made of white opaque glass.

The vacuum inclosing tubes 1 may be as long as the refrigerator is high or wide, as shown at the right and at the top of Fig. 6; or they may be as long as some divisional portion of the refrigerator, as shown at the left and bottom of Fig. 6; or if the dimensions of the refrigerator are large or if for other reasons found desirable the tubes 1 may be made in any suitable lengths and placed in the wall so that the tubes of one layer overlap the tubes of another layer in an endwise or longitudinal direction. The interlocking U-shaped tubes will then overlap each other in two directions parallel with the wall (transversely and longitudinally) and also in a direction perpendicular to the wall (due to the fact of the interlocking of the U-shaped tubes). This latter construction of heat barrier is illustrated in the back wall of the refrigerator shown in Fig. 6. This construction would more often be employed in the walls of cold storage buildings and the like. In this construction sealing and cushioning strips 17 are placed between adjacent ends of the vacuum inclosing tubes.

In the modified form of my invention shown in Figs. 4 and 5 two shapes or forms of vacuum inclosing bodies or vacuum tubes

are employed and are disposed laterally alternately to form a heat barrier. Larger elongated vacuum inclosing bodies or tubes 7 are provided having opposite grooves and 5 smaller vacuum inclosing tubes 8 of oval or elliptical shape and adapted to fit into the grooves of adjacent tubes 7, so as to provide a long and tortuous path through the wall along the material of the tubes. The joints

10 between the tubes are sealed and the tubes cushioned from each other by interposed gaskets 9 of yielding low heat conductive material. Two adjacent larger tubes 7 are shown as substantially surrounding a smaller

15 tube 8 with portions of one grooved tube 7 lying adjacent to portions of another grooved tube 7 at opposite sides of a smaller oval tube 8, thereby providing a longer path between the tubes through the low heat conductive material of the tubes and gaskets.

20 The principle of operation is the same as in the construction described above.

The modification shown in Figs. 7 and 8 comprises cylindrical pipes or tubes 10 in-

25 closing vacua and arranged in two layers, the pipes of one layer laterally overlapping or breaking joints with those of the other layer. By the lateral overlapping a longer path is provided through the wall between

30 the cylinders. Also owing to the fact that each cylinder in one layer enters partly between two cylinders in the other layer, the cylinders to some extent overlap each other in a direction perpendicular to the wall.

35 Also the cylinders of the different layers overlap each other in a lengthwise or longitudinal direction as indicated in Fig. 8 and substantially in the same manner as the tubes 1 (Fig. 6) overlap longitudinally, with

40 the exception that in the construction illustrated in Fig. 8 the cylinders 10 in each layer are also shown as breaking joints one with another longitudinally. The vacuum inclosing cylinders 10 are sealed together

45 and cushioned one from another by interposed gaskets 11 and 12 of yielding low heat conductive material. The gaskets 11 lie between adjacent cylinders in the first or outer layer and are prolonged inwardly as shown

50 so as to lie also between the layers or between the cylinders belonging to different layers, and the gaskets 12 lie between adjacent cylinders in the second or inner layer. Sealing and cushioning pads or washers 13

55 are interposed between the ends of longitudinally adjacent cylinders in each layer.

In the further modification shown in Figs. 9, 10, 11 and 12 substantially rectangular vacuum inclosing bodies or units 14 are 60 shown as employed. These bodies 14 are laid up with gaskets 15 and 16 of waterproof low heat conductive material interposed between adjacent bodies. In the construction shown in Fig. 11 the shell of the 65 vacuum inclosing unit is thick enough to

withstand the atmospheric air pressure on the outside thereof, but, for the sake of lightness, the shell may be made thinner and a support for the sides provided as shown in Fig. 13.

70 It is obvious that various modifications may be made in the constructions shown and above particularly described within the principle and scope of my invention.

I claim:

75 1. A heat barrier comprising a vacuum inclosing body provided with a groove, and a low heat conductive body adapted to enter the groove.

2. A heat barrier comprising a vacuum 80 inclosing body provided with a groove, and a second vacuum inclosing body adapted to enter the groove in the first body.

3. A heat barrier comprising a vacuum 85 inclosing body provided with a groove, a second vacuum inclosing body adapted to enter the groove in the first body, and a low heat conductive gasket in the groove between the two bodies.

4. A heat insulating wall comprising an 90 assemblage of adjacent vacuum inclosing bodies, each such body being provided with a groove in which portions of two other of the vacuum inclosing bodies are adapted to enter.

95 5. A heat insulating wall comprising an assemblage of adjacent vacuum inclosing bodies, each such body being provided with a groove in which portions of a plurality of the other vacuum inclosing bodies are adapt- 100 ed to enter.

105 6. A heat insulating wall comprising an assemblage of adjacent vacuum inclosing bodies, each such body being provided with a groove in which portions of two other of the vacuum inclosing bodies are adapted to enter, a low heat conductive gasket in each groove, and low heat conductive gaskets between the portions of the bodies entering the groove.

110 7. A heat insulating wall comprising an assemblage of adjacent vacuum inclosing bodies, each such body being provided with a groove in which portions of two other of the vacuum inclosing bodies are adapted to enter, a continuous sheet of low heat conductive material in the grooves and extending from groove to groove, and low heat conductive gaskets between the portions of the bodies entering the grooves.

115 8. A heat insulating wall comprising a layer of adjacent vacuum inclosing bodies, and a second layer of adjacent vacuum inclosing bodies adjacent to the first layer, the bodies of the second layer breaking joints 120 with the bodies of the first layer.

125 9. A heat insulating wall comprising a layer of adjacent vacuum inclosing bodies, a second layer of adjacent vacuum inclosing bodies adjacent to the first layer, the bodies 130

- of the second layer overlapping the bodies of the first layer in a plane parallel with the wall and also in planes substantially perpendicular to the wall, a low heat conductive sheet interposed between the layers, and low heat conductive gaskets interposed between the bodies in the layers.
10. A heat insulating wall comprising an assemblage of vacuum inclosing bodies arranged to form a plurality of adjacent layers, the bodies of adjacent layers overlapping one with another in a plane parallel with the wall and also in planes substantially perpendicular to the wall, a low heat conductive sheet interposed between the layers, and low heat conductive gaskets interposed between the bodies in the layers.
11. A heat barrier comprising transversely U-shaped vacuum inclosing tubes adjacently assembled and alternately oppositely arranged and interlocking one with another.
12. A heat barrier comprising U-shaped vacuum inclosing bodies adjacently assembled and alternately oppositely arranged and interlocking one with another.
13. A unit for heat insulating construction comprising a substantially U-shaped vacuum inclosing body having the legs of the U extending substantially parallel to each other for an appreciable distance.
14. A heat insulating wall comprising a layer of adjacent U-shaped vacuum inclosing bodies assembled with the U legs all extending toward one side of the wall, and a second layer of like bodies adjacent to the first layer and assembled with the U legs of the second layer all extending toward the first layer and toward the other side of the wall, the U legs of each layer extending between the U legs of the adjacent layer.
15. A heat insulating wall comprising a layer of adjacent U-shaped vacuum inclosing bodies assembled with the U legs all extending toward one side of the wall, and a second layer of like bodies adjacent to the first layer and assembled with the U legs of the second layer all extending toward the first layer and toward the other side of the wall, the U legs of each layer extending between the U legs of the adjacent layer, all of the U legs in both layers being arranged substantially parallel one with another.
16. A heat insulating wall comprising a layer of adjacent U-shaped vacuum inclosing bodies assembled with the U legs all extending toward one side of the wall, a second layer of like bodies adjacent to the first layer and assembled with the U legs of the second layer all extending toward the first layer and toward the other side of the wall, the U legs of each layer extending between the U legs of the adjacent layer, a low heat con-

ductive sheet interposed between the layers, and low heat conductive gaskets interposed between the bodies in the layers.

17. A heat insulating wall comprising a layer of adjacent U-shaped vacuum inclosing bodies assembled with the U legs all extending toward one side of the wall, a second layer of like bodies adjacent to the first layer and assembled with the U legs of the second layer all extending toward the first layer and toward the other side of the wall, the U legs of each layer extending between the U legs of the adjacent layer, all of the U legs in both layers being arranged substantially parallel one with another, a continuous sheet of low heat conductive material interposed between the layers, and low heat conductive gaskets interposed between the bodies in the layers and arranged so as not to touch the sheet which is between the layers.

18. A unit for heat insulating construction comprising a transversely U-shaped vacuum inclosing tube having the legs of the U extending substantially parallel with each other for an appreciable distance.

19. A heat insulating wall comprising transversely U-shaped vacuum inclosing tubes adjacently assembled in substantial parallelism with the plane of the wall.

20. A heat insulating wall comprising transversely U-shaped vacuum inclosing tubes adjacently assembled in substantial parallelism one with another.

21. A heat insulating wall comprising vacuum inclosing tubes adjacently assembled in substantial parallelism with the plane of the wall and arranged to form a plurality of adjacent layers substantially parallel with the plane of the wall and with the tubes in one layer breaking joints with the tubes in an adjacent layer, and low heat conductive gaskets interposed between the layers and between the tubes in the layers.

22. A heat insulating wall comprising a layer of adjacent vacuum inclosing bodies, a second layer of adjacent vacuum inclosing bodies adjacent to the first layer, the bodies of the second layer breaking joints with the bodies of the first layer, a low heat-conductive gasket interposed between the layers, and low heat-conductive gaskets interposed between the bodies in the layers and arranged so as not to touch the gasket which is between the layers.

In testimony whereof I affix my signature in presence of two witnesses.

CLYDE J. COLEMAN.
